Primary Examiner — Holly Baynham(74) Attorney, Agent, or Firm — Karuna Ojanen; Ojanen Law OfficesCLAIM

I claim the ornamental design for a purse, as shown and described.

DESCRIPTION

FIG. 1 is a front, perspective view of a purse showing my new design;

FIG. 2 is a perspective view of the purse unfolded thereof; FIG. 3 is top plan view of the purse unfolded; and, FIG. 4 is an enlarged perspective view of the interior of the purse.

The dotted and shaded areas in FIG. 11 represent slits along the striations of the horned back on the interior of the purse and are part of the claimed design.
